DOOR LATCH

Edwin H. Waterman, Munhall, Pa.

Application December 30, 1936, Serial No. 118,398

3 Claims. (Cl. 105—308)

This invention particularly relates to an adjustable door latch which is adapted to be used on heavy doors, such as those on railway hopper cars.

5 One of the objects of this invention is to provide a door latch which can be installed with a minimum amount of labor.

Another object of this invention is to provide a door latch with a hook member which has a 10 plurality of positions in which it can be assembled.

The foregoing and further objects will be made apparent by referring to the following description and the accompanying drawings, in which:

15 Figure 1 is an elevation of one embodiment of my invention;

Figure 2 is an elevation of my improved door latch after the initial step in the assembly thereof;

Figure 3 is a transverse sectional elevation on 20 line III—III of Figure 2;

Figure 4 is an elevation of my improved door latch after being further assembled; and

Figures 5, 6 and 7 are elevations of modifications of my invention.

25 Referring more particularly to the drawings, the numeral 2 indicates generally a door latch which is mounted on a hopper 4 of a railway hopper car (not shown). The hopper 4 has a side-plate 6 and a door 8 which is hinged at its upper edge. A filler-plate 10, or other suitable means, is secured to the side-plate 6 to provide a base for the remainder of the door latch 2. The filler-plate 10 has holes 11, a hole 12, and a hole 13 therein which align with holes previously made 30 in the side-plate 6. Initially the filler-plate 10 is secured to the side-plate by a rivet, or other suitable means, through the hole 13 and thereby held in its ultimate position.

A hollow trunnion 14 is formed integral with 40 the filler-plate 10 and surrounds the hole 12. A hook 16, having a bearing aperture 18, is fulcrumed on the trunnion 14. The hook 16 is adapted to be adjusted relative to a keeper-bar 17 secured to the door 8. The keeper-bar 17 is 45 fixedly positioned on the door 8 and is adapted to be engaged by the hook 16. However, relatively large tolerances are permitted in constructing the hopper 4 so that the position of the trunnion 14 relative to the keeper-bar 17 varies 50 considerably in different hoppers. Therefore, the position of the hook 16 on the trunnion 14 must be variable in order to position the hook 16 thereon in proper relation to the keeper-bar 17. To pivotally mount the hook 16 on the trunnion 14, the hook may be provided with a bear-

ing block 20, adjustable lengthwise of the bearing aperture 18. The bearing aperture 18 is of such size that the hook 16 can be adjusted appreciably relative to the keeper-bar 17 by shims 22 or similar devices.

5 In Figures 5, 6 and 7 I have shown modified forms of bearings for the hook 16. In this construction a split or two-piece bearing 21 is substituted for the bearing block 20. The halves of the bearing 21 may be of varying dimensions lengthwise of the bearing aperture 18 in the hook 16, as shown in Figures 6 and 7, so as to provide for adjustment of the hook relative to the keeper-bar 17 without the use of separate shims.

10 A bracket 24, having holes 26 therein which are in the same relative position as the holes 11 and 12 in the filler-plate 10, may be used as the outer member of the door latch 2. Rivets, or other suitable means, are placed through the holes 26, 11 and 12 and the side-plate 6 to permanently secure the door latch 2 to the hopper 4. The bracket 24 may pivotally carry a pawl 28 which is adapted to bear upon the hook 16 and lock it in engagement with the keeper-bar 17. A flange 30, having an aperture therein, may 15 be associated with the bracket 24 to facilitate the use of a crow-bar, or the like, in closing the door 8. The motion of the hook 16 may be limited by a stop 32 which is carried by the bracket 24.

20 While I have shown and described a specific embodiment of my invention, it will be understood that I do not wish to be limited exactly thereto, since various modifications may be made without departing from the scope of the invention as defined by the following claims.

30 I claim:

1. A door latch including a filler-plate adapted to be individually secured adjacent a door, a trunnion associated with said filler-plate, a hook 40 having a bearing aperture therein, a bearing block mounted in said bearing aperture and adjustable lengthwise thereof, said bearing block being fulcrumed on said trunnion, and shims for adjustably positioning said hook on said trunnion.

45 2. A door latch including a filler-plate adapted to be individually secured adjacent a door, a trunnion associated with said filler-plate, a hook having a bearing aperture therein, a bearing block mounted in said bearing aperture and adjustable lengthwise thereof, said bearing block being adapted to be fulcrumed on said trunnion, shims for adjustably positioning said bearing block in 50 said bearing aperture, a bracket for holding said hook and said bearing block on said trunnion, and 55

means securing said bracket and further securing said filler-plate adjacent said door.

3. The combination with the hopper of a railway car having a hinged closure, of a latch mechanism comprising a keeper-bar secured to and extending from said hinged closure, a filler-plate secured to the side-plate of said hopper adjacent said keeper-bar, a trunnion associated with said filler-plate, a hook having a bearing

aperture therein, a bearing block mounted in said bearing aperture and adjustable lengthwise thereof, said bearing block being fulcrumed on said trunnion, and shims for adjustably positioning said bearing block in said bearing aperture whereby said hook can be properly positioned relative to said keeper-bar. 5

EDWIN H. WATERMAN.
